UNITED STATES PATENT OFFICE.

HOWARD WEBSTER PARTLOW, OF UTICA, NEW YORK.

THERMOSTATIC GOVERNOR FOR GAS OVENS.

Application filed September 20, 1922. Serial No. 589,375.

To all whom it may concern:

Be it known that I, HOWARD WEBSTER PARTLOW, a citizen of the United States, residing at Utica, in the county of Oneida and State of New York, have invented certain new and useful Improvements in Thermostatic Governors for Gas Ovens, of which the following is a specification.

This invention relates to improvements in thermostatic governors for gas-heated appliances, and has for its object to provide a fuel governing mechanism, which may be applied to any gas heater, for automatically maintaining any desired predetermined temperature, whereby cooking, baking, as well as other forms of heating may be economically and accurately effected. And a particular object is to provide a thermostatic governor for gas-ovens and the like, which

20 is novel, simple and inexpensive, and which effectually prevents excessive heating, as well as waste of the fuel.

I attain these objects by the means set forth in the detailed description which follows, and as illustrated by the accompanying drawings, in which—

Figure 1 is a front elevation of an ordinary kitchen gas-range with the oven doors removed, to which my governor is applied: 30 Fig. 2 is an end elevation of the range. Fig. 3 is an enlarged side elevation of the governor. Fig. 4 is a central vertical section, taken on line 4—4 of Fig. 5; showing the construction, arrangement and operation 35 of the governing parts. Fig. 5 is a rear-face view of the body with the cover removed. Fig. 6 is a top-plan view of the body. Fig. 7 is a detached view of the link mechanism through which the thermostatic 40 element operates the gas valve. And Fig. 8 is a rear-edge view of the same.

In the drawings, 2 represents an ordinary gas-range, and 2' is the oven. 3 represents the usual tubular burners, which extend 45 transversely through the lower portion of the oven 2', the corresponding ends of the burners being fitted with the usual funnel-shaped mixers 3', which ordinarily receive the fluid or gaseous fuel from a common 50 manifold 4, by means of separate pipes 4'. The gas is supplied to the manifold by a pipe 4', which is preferably divided internally by a plug 4", and at the opposite sides of the said plug the said pipe is tapped by

similar nipples 4"—4", which conduct the 55 gas towards and from the thermostatic governor, which will now be described.

5 represents the hollow body of the governor, which has one open side that is normally closed and sealed gas-tight by a cover 60 5' and a packing 5", which are held in place by screws 5". Depending from the bottom of the body is a reduced portion 5", which is provided with a gas-receiving opening 5", the latter connecting with the nipple 4" by a pipe 4". The part 5" is also provided with a similar threaded gas-outlet opening 5", the gas being conducted from the latter opening towards the nipple 4", by a pipe 4". Within the body 5 is disposed a tubular valve casing 6, whose lower end 6' is threaded into the passage 5", the interior of said casing being formed with an annular seat 6" for a spherical valve 7, which controls the delivery of the fuel to the oven burners 3. The plug 4" is employed for diverting the fuel gas from one portion of the pipe 4" towards the body 5, from which it is returned to the other portion of the pipe 4" and the manifold 4. The valve 7 is adjustable to a certain extent 75 manually for predetermining the feed of the fuel to the burners, and the said valve is also automatically controlled during the heating operations by a thermostatic member 8, which preferably comprises an elongated brass or other tube 8' of relatively high expansibility, and a rod 8" preferably composed of steel or like hard substance of relatively low expansibility. The thermostatic elements 8"—8" loosely telescope each 80 other, except at their opposite ends where they are preferably only frictionally connected as shown. One end of the tube 8' is threaded for screwing into a threaded opening 5" of the body, which positions the member 8" at right angles to the longitudinal axis 85 of the body 5. The outer or free end of the tube 8' is preferably closed and internally is formed with a socket 8", which receives the outer end of the rod 8" and holds the said rod substantially concentrically in the tube. Adjacent the body 5 the rod 8" is provided 90 with an annular shoulder 8", which operatively fits the bore of the tube, and its inner end is formed into a finger 8", which normally projects beyond the corresponding end 100 of the tube 8' and is in constant operative engagement with the governing mechanism

2 contained in the body 5. The valve 7 is supported when unseated by a rod 7', whose upper end is secured to a lug 10' of a bar 10, the upper end of said bar being pivoted to one end of a link 11 by a pin 11'. The link 11 is pivoted near its middle by a pin 11^a to a sleeve 12, the latter having its lower end slotted at 12' to receive the link 11. The opposite end of the link 11 is pivoted to a similar vertically disposed link 13 by a pin 13', the lower end of the link 13 being pivoted to the long arm of a bell-crank lever 14 by a pin 13^a. The short arm of the lever 14 is pivoted by a screw 14' to a block 15, the latter being rigidly secured to the inner wall of the body 5 by screws 15'. The tip 14^a of the bell-crank, which extends above the pivot 14' is disposed opposite the opening 5' of the body and directly in the path 20 of the finger 8^a, the said parts being held constantly engaged by a spring 14^c. A second spring 14^a has one end thereof secured to the link 11 through the medium of a pin 14^a, the other end of said spring being secured to the top of the body 5 by any suitable means such as a screw 14^t, for equalizing and holding the movable parts in adjusted position. By this construction and arrangement of the parts, the lengthening and 30 shortening of the rod 8^a by the changing temperature of the oven 2', correspondingly rocks the bell-crank 14 on its pivot 14' for raising and lowering the valve 7 (see full and dotted lines in Fig. 7), which may be 35 accomplished by the link 11 being rocked vertically on the pivot 11'.

The sleeve 12 is supported by a vertically disposed screw 16, which is adjustably supported by a bushing 17, the latter being threaded into the top-end of the casing 5, as shown in Fig. 4. The sleeve 12 being held from rotation by the link 11 moves vertically on the worm 16. The worm 16 extends through the bushing 17 and supports a cylindrical dial 18, the latter having a hub 18' which supports a set-screw 18^t, by which the dial is made rigid to the worm. To the top end of the screw 16 is fitted a hand-knob 19, by which the screw may be rotated for raising and lowering the sleeve 12 and for correspondingly raising and lowering the link 11 and the valve 7, as shown by the full and dotted lines in Fig. 4, for predetermining the temperature of the oven 2', for baking, cooking and the like. The dial 18 is graduated and numbered, as best seen in Figs. 3 and 5, and the various adjustments are conveniently indicated by a pointer 20, which is supported by the top end of the body 5. In Fig. 3 the dial is shown set for indicating an oven temperature of 400°, which for example is the temperature required for baking bread, and certain other articles, as shown by a table or schedule 21, 60 which is inscribed on the front face of the

body 5 (see Figs. 1 and 3). The table 21 forms an important feature of the thermostatic governor when taken in connection with the dial 18, and the governor cannot be intelligently operated without these two important elements. Every different article placed in the oven 2', as a rule, requires a certain temperature and time for baking or cooking the said article. The table 21 has been compiled after consulting the highest authorities on food preparation and heating generally, so that when the present governor is adjusted and set according to the dial for a given temperature, like 400°, as shown, the said adjustment is made in accordance with the table 21, and the result of the cooking operation will be exactly what the predetermined or indicated temperature will produce. The worm 16 being supported entirely by the bushing 17, its rotation in opposite directions correspondingly raises and lowers the sleeve 12, as shown by the dotted lines in Fig. 4. After the governor has been adjusted, as described, the regulation of the supply of the fuel gas to the burners 3 is controlled entirely by the thermostatic member 8, and in order to understand this latter regulation reference may be had to Fig. 7 of the drawings. Assuming that the dial 18 has been set for say 400°, the burners 3 are lighted, and at that particular moment the regulating mechanism, consisting of the valve 7, bar 10, links 11 and 13, bell-crank 14 and rod 8^a, as well as the sleeve 12 will all be in the positions shown by the full lines in Fig. 7. The several parts will remain in the last named position as long as the temperature of the oven registers 400°. But as soon as the temperature of the oven rises above 400°, the expansion or lengthening of the tube 8' frees the rod 8^a sufficiently to effect the relaxing of the tension or pressure of the finger 8^a against the tip 14^a of the bell-crank. This effects the leftward movement of the said tip and the corresponding upward swing of the longer arm of the bell-crank 14, which is constantly under the tension of the spring 14^c. The upswing of the bell-crank through the link 13 correspondingly rocks the link 11 in the direction for lowering the valve 7 towards its seat in the casing 6, thereby reducing the flow of the gas towards the burners 3. The reduction of the gas instantly effects the lowering of the temperature to the predetermined degree, viz., 400°, for example, in accordance with the adjustment of the dial 18, as described. In case the temperature of the oven falls below 400°, the cooling of the oven effects the contraction of the tube 8', which forces the rod 8^a endwise towards the lever 14 and causes the tilting of said lever and related parts in the proper direction for lifting the valve 7 away from its seat for increasing the supply of gas to the burners 3. The 100 105 110 115 120 125 130

threads of the screw 16, in the present device are so arranged that the entire range of adjustment of the dial 18, so far as the pre-determining of the temperature of the oven is concerned, may be effected by a single revolution of the dial 18. To this end I provide a stop pin 22, which is mounted on the top of the body 5 in the path of a similar pin 23, which is carried by the dial (see Figs. 3 and 4). These pins are preferably arranged to engage when the pointer points to the neutral line α , shown in Fig. 5. A small pipe 24 connects with the supply pipe 4^a beyond the plug 4^b, and then extends into the oven alongside of the burners 3, for providing one or more pilot lights 24', for igniting the burners whenever the oven is to be operated.

Owing to the size of the oven 2', it is necessary to provide a relatively long thermostatic member 8, in order to properly regulate the temperature of the oven.

For the outer thermostatic member, as 8', I employ a metal of great expansibility, which preferably has a very high fusing point, while the inner thermostatic member, as 8^a, preferably comprises metal having the lowest expansion. Practice however, has proven that the relatively long tube 8' has too great linear variation to admit of fine and close adjustment of the fuel regulating parts. In order to overcome this trouble, the rod 8^a is preferably made in two parts, *c* and *d*, as shown in Fig. 3, wherein the part *c* preferably comprises a short section of common Bessemer steel, while the longer part is preferably made of "invar" steel. In the present device, the part *c* is relied upon for effecting practically the entire linear expansion and contraction of the secondary thermostatic element 8^a, it being well-known that "invar" steel has scarcely any expansibility. By this construction and arrangement, the linear variations of the element 8^a are so very slight that so small a change in the temperature of the oven as one-half degree or even less, will result in increasing and decreasing the flow of the gas to the burners 3, for maintaining the temperature of the oven at any predetermined stage.

Having thus described my invention, what I claim, is—

1. In combination with a burner and a valve for controlling the supply of fuel thereto, a thermostat arranged to be acted on by the heat from the burner and including a movable element, a rockable lever having a fixed fulcrum and one end disposed to be engaged and actuated by said movable element, a second lever, an adjustable fulcrum mounting the second lever between its ends for positive adjustment, a link connecting the other end of the first lever to one end of the second lever, and a second link

connecting the opposite end of the second lever to the valve for controlling the same.

2. In combination with a burner and a valve for controlling the supply of fuel thereto, a hollow body inclosing the valve, a thermostat mounted on the body and extending therefrom into the heat zone of the burner, said thermostat including a movable element projecting into the hollow body, a fulcrum block within the hollow body adjacent the projecting end of said movable element, a lever pivoted between its ends to the block with one end overlying the projecting end aforesaid, spring means normally urging said overlying end against said projecting end of the element, a second lever, a fulcrum support mounted for adjustment and pivoting said second lever between its ends, a link connecting the opposite end of the first lever to one end of the second lever, and means connecting the opposite end of the second lever to the valve.

3. In a thermostatic governor for gas ovens, a hollow body, a thermostat extending laterally therefrom and including a movable element projecting into the hollow body, a fuel valve in one end of the hollow body for controlling the supply of fuel to the burner of the gas oven, a fulcrum support adjustably mounted in the opposite end of the hollow body for adjustment toward and from the valve, a lever pivoted between its ends to the support, means connecting one end of the lever to the valve, a second lever having a fixed pivot in the hollow body and arranged to be actuated by the movable element, and means connecting the opposite end of the first lever to the second lever for operation thereby.

4. A thermostatic governor for gas ovens according to claim 3, characterized by the fulcrum support comprising a worm shaft journaled in said opposite end of the hollow body, a sleeve supported by the worm shaft and pivotally connected to the first lever for supporting the same, and spring means urging the second lever into contact with the movable element.

5. A thermostatic governor for gas ovens according to claim 3, characterized by the fulcrum support comprising a worm shaft journaled in said opposite end of the hollow body, a split sleeve providing a fulcrum support carried by the worm shaft for vertical adjustment therewith and pivotally connected to the first lever between its ends for supporting the same, spring means urging the second lever into contact with the movable element and other spring means adapted to equalize and hold the movable parts in adjusted position.

In testimony whereof I affix my signature.

HOWARD WEBSTER PARTLOW.
